NOZZLE SPRAY REGULATOR

Earl E. Thomas, Detroit, Mich.

Application April 22, 1940, Serial No. 330,900

13 Claims. (Cl. 299—76)

This invention relates to nozzle spray regulators and particularly to certain improvements on the structure shown by Patent 1,767,161, issued June 24, 1930, to T. J. Weaver.

An object of the invention is to provide a simpler type of spray regulator than that disclosed by said Weaver patent and to further simplify the Weaver device as regards mounting of the regulator on a stake carried by the nozzle.

Another object is to adjustably pivot a spray regulator on a stake carried by a nozzle, and to adapt such regulator to be securely retained in selective positions of adjustment.

A further object is to provide spring means resisting accidental shifting of a pivotal spray regulator from a selected angular position thereof, such means yielding when the regulator is manipulated to change its adjustment.

A further object is to pivot a spray regulator on a spring element applying a stress serving to hold the regulator definitely adjusted while affording its manipulation to change the adjustment.

A further object is to pivotally mount a nozzle spray regulator on a spring element engaging one edge of a stake carried by the nozzle, and to further utilize the spring element to yieldably hold the regulator engaged with a serrated opposite edge of the stake.

These and various other objects the invention attains by the construction hereinafter described and illustrated in the accompanying drawing, wherein:

Fig. 1 is a side elevational view of a nozzle equipped with my improved spray regulator.

Fig. 2 is a cross sectional view of the same, taken on the line 2—2 of Fig. 1.

Fig. 3 is an axial vertical sectional view of the nozzle and regulator.

Fig. 4 is a perspective view showing engagement of a bowed spring with a shoulder of the stake.

Fig. 5 is a cross sectional view of the stake, taken on the line 5—5 of Fig. 1.

Fig. 6 is a vertical sectional view of a modified construction.

Fig. 7 is a cross sectional view of such modification taken on the line 7—7 of Fig. 6.

Fig. 8 is a side elevational view of a further modification.

Fig. 9 is a cross sectional view of the further modification, taken on the line 9—9 of Fig. 8.

In these views, the reference character 1 designates a nozzle having an inlet 2 threaded for connection with a garden hose indicated at 3,

and having a relatively small outlet 4 coaxial with the inlet. Rigidly connected to the nozzle and preferably integral therewith, is a stake 5 pointed at its free end so that it may be readily pressed into the ground to support the nozzle in a desired position. Preferably said stake has a width materially exceeding its thickness, the approximate plane determined by its width and length being such as to include the nozzle axis.

10 The portion of the stake adjoining the nozzle is increased in width, as indicated at 6 and passes through a slot 7 formed in the mid portion of a spray regulator 8. Forwardly of said mid portion the spray regulator comprises a deflecting plate 9 having a substantially semi-circular free end, and rearwardly of said portion the regulator has a downward inclination and flares rearwardly to an increased width as indicated at 10.

20 Describing now the pivotable support for the spray regulator, a spring 11 formed of strip sheet metal extends through the slot 7 between spaced upper and lower shoulders 12 and 13 formed on the front edge of the stake 5, said spring being bowed to clear said edge between said shoulders and the spring width being substantially equal to the thickness of the stake. The upper of said shoulders is in close proximity to the outlet end of the nozzle, so that the latter

30 resists expansion of the spring 11 upwardly. At a suitable point between its ends, the spring 11 is formed with a small U-bend 14 extending toward the stake, and fitted into such bend is a half-round pivot member 15 formed integrally with the spray regulator as a projection from the front edge of the slot 7. The rear edge of said slot is rounded to form a tooth selectively engageable in any of a series of shallow pockets 16 formed by serrating the rear edge of the relatively wide upper portion 6 of the stake, such serrated edge forming an approximate arc centered at the pivot point of the spray regulator.

35 This arrangement subjects the spring 11 to a constant slight distortion, tending to maintain any selected engaged relation of the spray regulator with the serrated edge and hence resisting angular shifting of the regulator. The rear end 10 of the regulator forms a finger piece to facilitate adjustment, and resistance offered by the

40 spring 11 may be readily overcome by pressure applied to such finger piece.

45

40

45

50

55

The portion 6 of the stake sufficiently conforms in thickness to width of the slot 7 to prevent material lateral play of the spray regulator, and the latter holds the spring 11 in place.

As an additional precaution against lateral escape of the spring extremities from the shoulders 12 and 13, it is preferred to notch the spring ends as indicated at 17 and to form the shoulders with slight protuberances 18 to fit within the notches 17.

From foregoing description, it is evident that the spring 11 forms a pivotal support for the spray regulator and further imposes a forward pressure on the regulator such as to yieldingly hold the rear edge of the slot 7 against the serrated edge of the stake and engaged in one of the pockets 16 of such edge.

In the modified construction shown in Figs. 6 and 7, there is provided a nozzle 1a with threaded inlet 2a and relatively small outlet 4a coaxial with the inlet. A stake 5a is rigidly carried by the nozzle and has its upper portion widened, as indicated at 6a. Such widened portion is accommodated within a slot 7a of a spray regulator 8a and the forward portion of the latter forms a deflecting plate 9a, the modification fully conforming as so far discussed to the first-described construction. From the front edge of the slot 7a there projects integrally a pivot member 15a for the spray regulator, and the front edge of the stake 5a is formed with a notch 19 to accommodate such pivot member. Extending from the rear end of the slot 5a to the rear end of the regulator 8a is a bore having its rear portion threaded to retain a screw 20. Compressed between such screw and a pin 21 slidable in said bore is a coiled spring 22 urging the rounded front end of the pin against the rear edge of the portion 6a of the stake, such edge 16a being serrated and forming an approximate arc centered at the pivot of the regulator. Thus the spring-pressed pin serves as a detent to yieldably maintain adjustment of the regulator, serving substantially the purpose of the spring 11 in the first-described construction. The finger-piece function of the rear portion 10a of the regulator is retained in the modification, in adapting such portion to mount the spring-pressed pin.

In the further modification shown by Figs. 8 and 9, the parts 1b, 2b, 4b, and 5b are substantially like the parts 1, 2, 4 and 5 first described. The spray regulator comprises a deflecting plate 9b and a pair of parallel arms 23 integral with and rearwardly projecting from said plate and straddling the widened upper portion 6b of the stake. Said arms are formed with aligned apertures and these are further aligned with a tapped aperture in the portion 6b to accommodate a screw 24 serving to pivot the spray regulator on the stake. Said screw has a wing head 25 or other suitable provision for clamping at least one of the arms 23 against the stake to hold the spray regulator selectively angularly adjusted.

In each of the described modifications it will be noted that the pivotal mounting of the spray regulator permits the deflecting plate (or deflector) thereof to intersect the axis of the nozzle outlet in selective angular relations to such axis, and in each case provision is made for maintaining any adjustment of the spray regulator, while permitting it to yield when manipulated.

When a jet of water discharging from the nozzle encounters the deflecting plate, it fans out to an extent determined by divergency of such plate to the jet and hence the resulting spray may be applied to a large or small area, as may be desired. By adjusting the deflecting plate to its lowermost position, it may be withdrawn from contact with the jet, so that the latter may have

75 a maximum range. When desired, the stake 5, 5a or 5b may be used as a handle for the nozzle, the finger-piece 10 or 10a being then readily operable by the thumb of the hand gripping said stake.

The entire device, in its various modified forms, is quite inexpensive and lends itself to production of the parts as die castings.

What I claim is:

1. A spray device comprising a nozzle having a discharge port, a member connected to and projecting from the nozzle, a spray regulator having a deflector exterior to the nozzle, said regulator being pivoted on said projecting member to afford angular movement of the deflector across the extended axis of the discharge port, a spring forming a pivot bearing for the regulator and reacting between the regulator and said projecting member, and means on the projecting member correlated with the regulator to yieldably resist pivotal movement of the regulator, responsive to said spring reaction.

2. A spray device comprising a nozzle having a discharge port, a spray regulator having a deflector and movable to intersect the deflector with the extended axis of said port at selective angles, a spring carried by the spray device and pivotally mounting the regulator to afford said angular movement of the deflector and means in engagement with the regulator resisting its pivotal movement, said spring yieldably urging the regulator into such engagement.

3. A spray device comprising a nozzle having a discharge port, a stake carried by the nozzle at an angle to the axis of the discharge port, a spray regulator having a slot to accommodate said stake and having a deflector, a spring pivotally mounting the regulator and thereby affording the deflector an angular movement across the extended axis of the nozzle and also a movement for restraining purposes, said spring reacting between the stake and an edge of said slot, to exert restraining pressure on the regulator, and means on the stake, and engaged by the regulator under pressure imposed by said spring to normally restrain the regulator for said angular movement.

4. A spray device comprising a nozzle having a discharge port, a member connected to and projecting from the nozzle and having a serrated edge, a spray regulator formed with a slot accommodating said projecting member and formed with a deflector, means pivoting the regulator at one end of said slot on said projecting member whereby the deflector may intersect the extended axis of the nozzle at selective angles to such axis, and means on the regulator at the other end of said slot coacting with said serrated edge to hold the regulator selectively adjusted.

5. In a spray device as set forth in claim 4, a spring reacting between said projecting member and the regulator to hold the regulator selectively adjusted.

6. A spray device comprising a nozzle having a discharge port, a member connected to and projecting from the nozzle, a spray regulator having a deflector, means pivoting the regulator on the projecting member to afford the deflector selective angular positions of intersection with the extended axis of said discharge port, said projecting member having a serrated edge in substantially the form of an arc centered at the pivotal axis of the regulator, and a spring-pressed detent on the regulator engageable with said

serrated edge to hold the regulator selectively pivotally adjusted.

7. A spray device comprising a nozzle, an elongated supporting member for the nozzle connected to and projecting from the nozzle, a spray regulating member including a deflector, one of said members having a portion formed with a serrated edge and the other member having a slot accommodating said serrated portion, means pivoting the regulating member at one end of said slot on the supporting member, whereby the deflector may be adjusted to intersect the extended nozzle axis at selective angles to such axis, and means on the slotted member at the other end of said slot coacting with said serrated edge 15 to hold the regulating member in a selective pivotal adjustment.

8. A spray device comprising a nozzle, an elongated supporting member for the nozzle connected to and projecting from the nozzle, a spray 20 regulating member pivoted on the supporting member and including a deflector, one of said members having a slot accommodating the other member, a spring at one end of said slot reacting between the two members to exert pressure on the regulating member, and an element at the other end of said slot engaged by the regulating member under pressure imposed by said spring and restraining the regulating member from accidental pivotal movement.

9. A spray device as set forth in claim 8, said spring having a mid portion occupying said slot and end portions projecting oppositely beyond the slotted member and seating on the other of said members, said mid portion forming a seat 35 pivotally engaged by the slotted member.

10. A spray device comprising a nozzle, an elongated member connected to and projecting from the nozzle, a spray regulating member including a deflector and pivoted on the first mentioned member to afford the deflector angular movement across the extended axis of the nozzle, one of said members having a slot to accommodate the other, a spring having its mid portion within said slot and providing a pivotal seat 40 for the slotted member, the end portions of said spring being seated on the other member and

notched to receive projections on the other member, and means interengaging said members under stress of said spring to resist accidental pivotal movement of the regulating member.

11. A spray device comprising a nozzle having a discharge axis, a support rigidly projecting from the nozzle in a direction substantially transverse to said axis, a pivotal spray regulator formed with a deflector for the stream discharged by the nozzle, said regulator being movable to intersect the deflector with said stream at selective angles, and having a slot accommodating said support, a spring pivotally seating the regulator for said movement and reacting between said support and one end of the slot to urge the regulator into a restraining engagement, at the other end of the slot, with said support, and means on the support correlated with the regulator to establish said restraining engagement.

12. A spray device comprising a nozzle having a discharge port, a member connected to and projecting from the nozzle and having opposite edges one of which is serrated, a spray regulator formed with a deflector, means pivoting the regulator on said projecting member at the other of said opposite edges, whereby the deflector may intersect the extended axis of the nozzle at selective angles to said axis, and means on the regulator coacting with said serrated edge to hold the regulator selectively adjusted.

13. A spray device comprising a nozzle, an elongated member connected to and projecting from the nozzle, a spray regulator including a deflector, said regulator having a slot to accommodate said elongated member, a spring having its mid portion within said slot and providing a pivotal seat for the regulator, to afford the deflector angular movement across the extended axis of the nozzle, the end portions of said spring being seated on the elongated member and notched to receive projections on the elongated member, and means in engagement with the regulator restraining it from accidental pivotal movement, said spring being so stressed as to yieldably urge said regulator into such engagement.

EARL E. THOMAS.
